J. F. KINGSLEY.
Oscillating-Engine.

No. 224,093.

Patented Feb. 3, 1880.

UNITED STATES PATENT OFFICE.

JOHN F. KINGSLEY, OF OWEGO, NEW YORK.

OSCILLATING ENGINE.

SPECIFICATION forming part of Letters Patent No. 224,093, dated February 3, 1880.

Application filed December 31, 1879.

To all whom it may concern:

Be it known that I, JOHN F. KINGSLEY, of Owego, in the county of Tioga and State of New York, have invented a new and valuable Improvement in Oscillating Engines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my improved engine without the frame. Fig. 2 is a front elevation of the same, partly in section. Fig. 3 is a detail view of the eccentric with forked end.

The object of the present invention is to improve the construction and operation of oscillating engines; and it consists in a peculiar valve-gear adapted to oscillating engines, by which the action of the valve is not materially affected, and by which it can be set to have more or less lap and lead, and also to cut off at longer or shorter stroke, all of which will be more definitely described hereinafter, and subsequently pointed out in the claims.

In the accompanying drawings, A represents the cylinder of an oscillating engine of the ordinary construction, and provided with 30 stuffing-box and piston-rod. The cylinder A has also a steam-chest, a, and slide-valve b, also of the usual construction, and on each side the trunnions B B'.

The trunnion B is provided with a square shoulder, C, upon which an auxiliary eccentric, D, moves up and down.

The eccentric D has a rectangular opening, d, in it to allow of such movement, and is held in position laterally upon the trunnion by 40 guide-pieces c c'.

The eccentric-strap E has a rod, e, which extends to a movable or stationary point at right angles or in line with the center of the cylinder and center of crank-shaft; but, for convenience, in this case it has a forked end, e', to receive the crank-shaft, on which it is free to slide on a line with the center of cylinder and center of shaft.

An adjustable collar, d', on the shaft S prevents lateral motion of the forked or upper end of the rod e upon the shaft. To the side of

the rod is pivoted a rod, f, of the main eccentric-strap F, that revolves on the main eccentric G, and is provided with the ordinary lugs and bolts for holding it in place thereon. 55

The eccentric D has a hub, H, extended on the side toward the valve-chest a, which is also provided with a rectangular opening to allow it to move on the square part of the trunnion. To this hub is secured an arm, h, bent at right angles, or nearly so, at its upper end, and is provided with a suitable hole for the reception of the end of the valve-stem I, which is connected in the ordinary manner to the valve b.

The piston-rod terminates in the usual stub end i, and revolves upon the crank-pin k, preferably arranged between the two crank-plates K, by which a steadier motion is obtained than by a single crank.

The operation is as follows: The eccentric D having been placed in its proper position on the trunnion B, and the main eccentric G arranged on the shaft S, the two rods are connected, as shown at l.

If it is desired at any time to alter lap and lead of the valve, the eccentric G is merely set either forward or backward in the ordinary manner on the shaft S, by which the valve obtains the proper movement through the medium of the bent arm h. The valve can also 80 be adjusted by the nuts n n on the valve-stem.

The great advantages of my improvement are, that a very great steadiness is imparted to the valve-stem and the eccentric-rods instead of the usual knuckle-joint. It is also 85 very simple in its construction and operation.

The parts of the engine constructed in accordance with my invention are not liable to get out of order, and can be easily repaired or replaced when found necessary. The valve 90 can be very easily adjusted to any desired point to cut off shorter or longer, and simply by giving more or less lap and lead to it.

Having now fully described my invention, what I claim as new, and desire to secure by 95 Letters Patent, is—

1. In an oscillating engine, the auxiliary eccentric D, provided with hub H, slot d, and bent arm h, in combination with the valve-stem I and the main eccentric G, the whole 100 constructed and arranged to operate substantially as and for the purpose set forth.

2. In an oscillating engine, the auxiliary eccentric D, provided with an extended hub, H, and slot d, in combination with the eccentric strap and rod E e, substantially as and for the purpose specified.

3. The combination of the cylinder A, the valve b, valve-stem I, bent arm h, and extended hub H with the eccentric D, strap E, trunnion B, provided with square shoulder C, and the main eccentric G, strap F, and shaft S, all constructed and arranged as shown, and for the purpose specified.

4. In an oscillating engine, the combination

of an oscillating cylinder and its valves with the auxiliary eccentric D, having hub H and slot d, bent arm h, eccentric-strap E, main eccentric G, and strap F, pivoted to the rod e, all arranged substantially as and for the purpose set forth.

In testimony that I claim the above I have hereunto subscribed my name in the presence of two witnesses.

JOHN F. KINGSLY.

Witnesses:

BARNEY M. STEBBINS,
CHARLES N. MATSON.
